PAGE 2

Figure 1 is a side elevational view of a monorail train, showing my new design;

Figure 2 is a side elevational view in enlarged scale of the middle car shown in Figure 1;

Figure 3 is an enlarged perspective view of the front car shown at the left of Figure 1;

Figure 4 is a front view of said front car;

Figure 5 is an enlarged perspective view of the rear car shown at the right of Figure 1; and

Figure 6 is a rear view of said monorail train.

The side not shown has substantially the same appearance as the side shown in the drawings.

The track shown in broken lines is included for illustrative purposes only.

I claim:

The ornamental design for a monorail train, substantially as shown and described.
